UNITED STATES PATENT OFFICE.

FRED E. ASELTINE, OF DETROIT, MICHIGAN, ASSIGNOR TO GENERAL MOTORS CORPORATION, OF DETROIT, MICHIGAN, A CORPORATION OF DELAWARE.

CARBURETOR.

Application filed July 31, 1919. Serial No. 314,210.

One well known type of carburetor comprises a strangle tube extending down around the upper end of a nozzle structure and provided with a tubular air valve movable vertically as a whole to admit more or less auxiliary air to the primary mixture in accordance with the speed of the engine, said air valve being actuated by the difference in pressure between the space 10 immediately around the nozzle and that above a disc-like fixture carried thereby and depending into the strangle tube.

One object of the present invention is to improve this type of carburetor so as to obtain both a correct idling mixture and a more lean or economical mixture at intermediate engine speeds. This I accomplish in the present instance by means of one or more by-pass passages through the strangle 20 tube so arranged as to admit air pressure to the space above the nozzle at the intermediate throttled speeds, said by-pass being positioned to admit relatively less air pressure under conditions of closed throttle such as in idling. Thus substantially the entire air supply is made to pass directly about the nozzle in idling and under conditions of low engine suction; when the suction increases to that corresponding to the intermediate throttled speeds, the by-pass passages admit air pressure and a diluting supply of air to the primary mixture in the strangle tube in addition to that which enters past the lower edges of the auxiliary 30 air valve proper, thereby reducing the suction effective on the nozzle, which, in turn, tends to reduce the amount of fuel delivered and to establish a more lean, economical mixture.

Another primary object is to provide a proper mixture throughout the range of service conditions corresponding to a given throttle position, that is, assuming the mixture is of the economical or lean type when the engine is running under favorable conditions (as when the vehicle is traveling at say twenty-five miles per hour on hard level roads), it is the purpose of the invention to provide a carburetor whereby the mixture is automatically enriched immediately upon an increase in load. Still another object is to insure a proper mixing of the primary air and fuel supply.

In the drawings, Fig. 1 is a vertical section showing a preferred embodiment of the

invention. Fig. 2 is a perspective view of the strangle tube, parts being broken away to show the blades or fins whereby the mixture current is given a whirling movement. Fig. 3 is a perspective view of one of the 61 blades.

The general construction of the carburetor to which the invention is shown as being applied is well known and includes the body 1 forming an air intake passage 2 and a mixture outlet 3, concentric for a part of their length and separated by the cylindrical wall or skirt or sleeve guide 4. Attached to the body in any suitable manner is a cover 5 for a float bowl 6, said cover 70 having a depressed central portion 7 forming a nozzle chamber 8 and tapped to receive the usual nozzle structure 9; and fuel is supplied in the ordinary way through the medium of the passage 12, valve 13 and 75 valve-controlling float 14.

15 designates a strangle tube positioned on the cover and extending down into the chamber 8 and spaced from the nozzle 9' to direct air, which passes from the passage 2 through a passage or passages 16 down into the chamber 8, upwardly about the end of the nozzle and into the upwardly flaring mixture passage 17 formed by the strangle tube itself. A tubular air valve or sleeve 18, guided by the wall 4, tends to drop to the position shown to thus close off direct communication between the annular passages 2 and 3 through the auxiliary air passage directly below the wall 4 when the engine is not running or when but little suction is applied to the outlet as in idling. This valve is provided with a fixture 18' including a disc-like element or lift-plate 18" at its lower end, said element being arranged to restrict the passage 17 more or less depending on the position of the air valve as well as the taper of the strangle tube 4. A retainer 20 clamped between the body and the cover affords a convenient 100 means for holding the strangle tube in place, this plate and the flange 21 on the inner surface of the guide 4 serving to limit the movement of the auxiliary air valve. The usual throttle valve appears at 22. 105 Formed in the cover is a passage 23 in communication with the interior of the nozzle and opening, under control of the needle valve 24, into a passage 25 which extends through the wall of the strangle tube and 110

has its outlet at an intermediate point in the height thereof. This passage provides the fuel supply for idling.

In accordance with the underlying principles of the invention, I form in the wall of the strangle tube, preferably at a point substantially opposite the disc-like element or lift-plate 18", a by-pass passage or passages 26 adapted to connect the chamber 8 with the chamber 17 and so arranged as to conduct but little, if any, air when the auxiliary air valve is in the position shown; that is, when the engine suction in the space anterior to the throttle is low, as in idling, the valve or disc 18" restricts the flow of air from below to such an extent that a relatively strong pull is exercised on the idling passage 23-25 to secure the proper amount of fuel. The throttle being gradually opened and the suction increasing, the lift-plate rises beyond the by-pass passages 26, and air pressure from the chamber 8 and a certain amount of air is admitted into the space below the disc or valve 18", and tends to more nearly satisfy the suction in the passage 17, in other words, to lean out the mixture as obtained from the idling passage; at the same time, however, the main nozzle 9' comes into action but not so intensely as would be the case were the by-pass passages omitted. These latter thus tend to admit air from the passage 8 to the space just above the nozzle 9' at the intermediate throttled speeds to thereby reduce the suction and establish a more lean or economical mixture for ordinary driving. At the same time, the transition or change of mixture from the relatively rich to the relatively lean is so gradual as to result in a highly desirable flexibility of operation. Assuming now that the throttle valve continues to open and that the suction further increases, more fuel is admitted from the jet 9' and more auxiliary air enters underneath the edge of the air valve as the latter rises; and the resulting mixture might become too lean for maximum power at open throttle were it not for the fact that the current of air entering the chamber 17 under conditions of open throttle and high speed from around the nozzle 9' flows up more nearly through the middle of the chamber and not directly across the outlets of the by-pass passages 26, from which it follows that a less quantity of air relatively to the total primary mixture, is bled in, and a rise in richness, or at least a proper maintenance of the existing richness to afford the desirable power mixture takes place.

Again, assuming that the throttle remains at a given position, say that corresponding to a speed of thirty miles per hour on favorable roads, and the load is increased as in climbing hills of medium height, the air

valve tends to sink which in turn causes the fuel mixture to build up in richness to compensate for the increased demand in power, and the action is essentially the reverse upon a reversal of conditions. Under conditions of very low speed at open throttle, this building up of the mixture in richness may be due to the tendency of the air valve to vibrate vertically and to thereby in effect restrict the by-pass passages.

That is, in this manner I automatically secure a desirable rich mixture for idling, a lean or economical mixture for intermediate throttled speeds, and a rich power mixture for open throttle speeds, the transition from one to the other being so gradual as to give rise to unusual smoothness of action or flexibility. Moreover, the character of the mixture depends on the load for, as explained heretofore, the by-pass passages automatically cause the richness of the mixture to build up as the load is added and to become less as the load decreases. It will also be seen that the apparatus includes an air intake of which the chamber 8 forms a part, a mixture chamber 17 and a by-pass passage or passages 26 by-passing the nozzle 9', together with means under the control of the engine suction for restricting or otherwise rendering the by-pass relatively inoperative for the flow of air at both low and high suctions, and particularly for causing or permitting it to function freely at suctions corresponding to the intermediate throttled engine speeds.

In order that the fuel may be more fully broken up, I prefer to form on the inner surface of the strangle tube inclined or helical blades or fins, these elements being, in the present instance, separate from the tube itself and inset in slots formed therein. As shown, they include the plane body portions 30 (the bases of which are received in the slots) having the inwardly extending projections 31 the upper corner portions 32 of which are bent forwardly in the direction of the inclination of the body portion. The primary air and fuel mixture is in effect split up into several channels and is caused to whirl around in the mixing chamber to disintegrate the small fuel globules and distribute them throughout the entire cross-section of the incoming air.

By proceeding in this manner the disintegrating influence is applied to much better advantage and the resulting mixture is much more homogeneous than would be the case were the fins or their equivalent positioned on the wall of the mixing chamber beyond the inlet for the auxiliary air, since they would in that event operate primarily on an envelope of air rather than on the entering stream of fuel mixture.

I am aware that the invention, both in respect to the by-pass passage and to the

mixing blades or fins, is applicable to carburetors other than that shown, and I do not, therefore, wish to be limited except as indicated by the subjoined claims.

5 I claim:—

1. A carburetor including a fuel chamber having a cover with a depression therein, a strangle tube depending into the depression, a fuel supply device leading from the fuel chamber and opening into the strangle tube, said strangle tube and cover forming an air intake passage leading down about the outside of the strangle tube and upwardly along the nozzle, the strangle tube forming a mixture passage for air from the intake passage and fuel from the nozzle and also having a by-pass passage for by-passing the nozzle and permitting air to flow from the intake to the mixture passage in said strangle tube to lean out the mixture at certain engine speeds, and movable means operative on said by-pass passage to restrict the flow of air therethrough at low engine speeds and to permit an increased flow of such air at intermediate engine speeds.

2. In a carburetor, a throttled mixture passage, means for supplying primary air thereto, means for supplying auxiliary air thereto, means for supplying fuel thereto, including a main fuel passage and an idling fuel passage opening thereto at different levels, a valve for controlling the admission of said auxiliary air, a suction controlled element operated by the inflow of primary air and acting to initiate the opening of said auxiliary air valve, and a bypass passage of small cross section operative to admit air to the mixture passage between the outlets of the fuel passages, the flow of air through said bypass passage being controlled by said element, whereby the quality of the fuel mixture is varied in accordance with the engine load and without manipulation of the throttle.

45 3. In a carburetor, a casing, a main fuel inlet and an auxiliary fuel inlet spaced therefrom longitudinally of the casing, a strangle tube into which said inlets open, said main fuel inlet being spaced from the strangle tube to afford an inlet for air into the latter, there being a passage through the strangle tube to by-pass the main fuel inlet and to admit pressure to the space im-

mediately about the main fuel inlet and between it and said idling fuel inlet, and suction controlled means for regulating the operation of said by-pass relatively to that of said air inlet.

4. In a carburetor, a throttled air passage having a restriction, a fuel inlet opening into the air passage adjacent the restriction, a suction controlled lift plate arranged to restrict said restriction as the suction falls, and a by-pass passage opening into said air passage substantially opposite the lift plate when the latter is in lowermost position, whereby the quality of the fuel mixture is varied in accordance with the engine load and without manipulation of the throttle.

5. A carburetor including a strangle tube open at its lower end, a main nozzle arranged to deliver fuel to the lower portion thereof, an idling fuel passage opening into said strangle tube beyond said main nozzle, a by-pass passage arranged to deliver air to said strangle tube below the upper end thereof and beyond said main nozzle, and a suction controlled member interposed between said main nozzle and the outlet of said idling fuel passage and cooperating with said by-pass passage to restrict the flow of air therethrough under certain conditions of suction.

6. A carburetor including a fuel chamber having a cover with a depression therein, a strangle tube depending into the depression, a main fuel nozzle leading from the fuel chamber and opening into the lower portion of said strangle tube, an idling fuel passage opening into said strangle tube at a higher level than said main nozzle, said strangle tube and cover forming an air intake passage leading down about the outside of the strangle tube and upwardly past said nozzle and said idling fuel passage, said strangle tube having a by-pass passage below the outlet of said idling fuel passage thereto, a mixture outlet passage including a guide, a tubular air admitting valve slidably therein and having a lift plate therefor arranged to cooperate with said by-pass passage to permit increased flow of air therethrough under conditions of intermediate engine speed.
